DESIGN FOR A STOPPER FOR A PERFUME BOTTLE

Frederic H. Hirsch, New York, N. Y., assignor to John Frederics Perfume Corporation, New York,
N. Y., a corporation of New York

Application July 22, 1935, Serial No. 57,779

Term of patent 7 years

To all whom it may concern:

Be it known that I, Frederic H. Hirsch, a citizen of the United States and a resident of New York city, in the county and State of New York, have invented a new, original, and ornamental Design for a Stopper for a Perfume Bottle, of which the following is a specification, reference being had to the accompanying drawing, forming part thereof.

I claim:

The ornamental design for a stopper for a perfume bottle substantially as shown.

FREDERIC H. HIRSCH.
